CLAIM

The ornamental design for a dual sided cat toothbrush, as shown and described.

DESCRIPTION

FIG. 1 is a front view of a dual sided cat toothbrush in accordance with the new design;

FIG. 2 is a rear view thereof;

FIG. 3 is a left-side view thereof;

FIG. 4 is a perspective view thereof;

FIG. 5 is another perspective view thereof;

FIG. 6 is an enlarged view of a portion 6 shown in FIG. 4;

FIG. 7 is an enlarged view of a portion 7 shown in FIG. 5; and,

FIG. 8 is an enlarged view of a portion 8 shown in FIG. 1. The broken lines shown in FIGS. 1, 4, 5, 6, 7, 8 are for the purpose of depicting enlarged view indicators, and form no part of the claimed design.
